UNITED STATES PATENT OFFICE.

ARTHUR W. CASH, OF DECATUR, ILLINOIS, ASSIGNOR TO UNITED STATES WIRE MAT COMPANY, OF DECATUR, ILLINOIS, A CORPORATION OF ILLINOIS.

IMPLEMENT OR DEVICE FOR KILLING OR DISABLING INSECTS, FLIES, OR THE LIKE.

1,380,355.

Specification of Letters Patent.

Patented June 7, 1921.

Application filed December 3, 1917. Serial No. 205,086.

To all whom it may concern:

Be it known that I, ARTHUR W. CASH, a citizen of the United States, a resident of Decatur, in the county of Macon and State 5 of Illinois, have invented new and useful Improvements in Implements or Devices for Killing or Disabling Insects, Flies, or the like, of which the following is a specification.

10 This invention relates to improvements in implements or devices for killing or disabling insects or the like, by striking, and the principal object of this invention is the provision of such a device which is simple 15 in construction, attractive in appearance and capable of withstanding extended use.

Another object of this invention is the provision of such a device, the body portion 20 of which is constructed so as to have maximum flexibility and strength, and in which the handle is securely connected to the body portion so as to strengthen the same and to reduce the possibility of breakage or separation between the handle and the body portion 25 of the device.

Further objects include the provision of such a device which is simple in construction and cheaply manufactured, and which will give extended use and service.

30 To the accomplishment of the foregoing and such other objects as may hereinafter appear, my invention consists in the combination, construction and arrangement of parts hereinafter described and then sought 35 to be defined in the appended claims, reference being had to the accompanying drawing forming a part hereof, which shows merely for the purpose of illustrative disclosure, a preferred embodiment of my invention, it being understood that various 40 changes may be made in practice within the scope of the claims without digressing from my inventive idea.

In the drawings,

45 Figure 1 represents an elevational view of one side of one form of device constructed according to this invention;

Fig. 2 is a similar view of a slightly different form of device constructed to embody 50 this invention;

Fig. 3 is a detail view showing the manner of securing the handle to the body of the device, taken on the other side of the body of the device shown in Fig. 1, and

55 Fig. 4 is an enlarged detail sectional view

through the edge binding and the additional binding and strengthening strip.

Referring now to the drawing, and first to Figs. 1, 3 and 4, the numeral 1 designates the body portion of the device. This is 60 preferably composed of a woven wire fabric or flexible netting, rectangular in shape and having its side and top edges provided with a binding 2 of suitable material, such as 65 felt or the like, for the purpose of increasing the attractiveness of the device and preventing damage or injury to the surfaces against which the device is struck.

The body portion may be provided with the medial reinforcements 3, if desired. The 70 lower corner portions of the body of the device are folded along lines 4 converging to a point, as shown, and slightly overlapping so as to provide a portion of three- 75 ply thickness. It is to be noted that the bound edge portions 5 converge toward each other and intersect, forming oblique reinforcements or braces.

The handle 6 is of a single piece of wire 80 looped as at 7 to provide the grasping portion twisted as at 8 and having the straight portion 9 extending to the twisted part 10, which extends to the point at the lower end of the body. The free end portions 11 of the wire are extended obliquely along the 85 line 4 on which the lower corner portions of the body are folded and within this folded part to a point near the edge of the body, at which point 12 these free end portions are bent so as to extend substantially 90 parallel to the bound edges 5. These free ends terminate near the middle of the body and afford strong braces and reinforcements for the body along the lines 4 on which the lower corner portions are folded and along 95 the lines 5 of the bound edges of the folded portions.

In order to hold the parts securely together, and to retain and hold the folded portions of the body closely thereto, I use 100 the plurality of rivets or staples 13 which are inserted through the binding adjacent the bend in the same, and which are also inserted through the binding adjacent the intersection of the folded portions thereof. 105 These last mentioned rivets or staples are also positioned adjacent and close to the ends of the wire member forming the handle, and therefore, not only hold the folded portions of the body closely to the body, 110

but also coöperate to hold the free end portions securely in place within the folded portions of the body.

As an additional securing means, I stitch the bound edges of the folded portions through the body and also provide on the other side, the additional strip of binding 14 as shown in Figs. 3 and 4 which prevents the stitching from being torn or ripped out in the use of the device. The twisted portions of the handle are for the purpose of giving it stiffness and rigidity, while the straight portions give the handle a slight resiliency so that it may act quickly and efficiently.

A slightly different form of my invention is shown in Fig. 2, wherein the body member 15 is substantially the same form as shown in Fig. 1, but does not have bound edges or the medial reinforcements. Instead, the side edge portions are folded over upon themselves a plurality of times as at 16, and thereby provide the side reinforcements. Due to the fact that the lower corner portions of the body are folded, these folded side edge portions extend obliquely across the lower portion of the body of the device and intersect each other, forming oblique reinforcements or braces 17. The handle is of the same construction, the only difference being in the length. The handle shown in Fig. 2 is of standard length, while that shown in Fig. 1 is extra long so as to enable the user to reach a greater distance. In the construction shown in Fig. 2, the plurality of the rivets or clamps 18 are utilized, extending through the folded portions of the netting and arranged substantially as arranged in the construction shown in Fig. 1, so that they operate not only to hold the folded portions of the body down against the body, but also hold the handle tightly and securely within the body.

What I claim is:

1. A device of the character described, including in combination a body portion, and a handle, said body portion being composed of flexible netting of substantially rectangular shape, having its side and top edges bound with a soft, flexible material and having its lower corner portions folded along lines converging to a point and slightly overlapping, said handle member being in

the form of a looped wire to provide the gripping portion and having its end portions free and positioned between the body portion and the folded corner portions, the end portions of the handle extending along lines on which the lower corner portions are folded and then bent and extended to substantially the intermediate part of the body portion, and securing means for connecting the upper edges of the folded corner portions to the body portion so as to hold these edges against the body portion and to hold the free end portions of the handle member therein, said securing means passing through the binding and the body portion and a strip of flexible material positioned on the side of the body opposite the binding in which the ends of the securing means are clenched.

2. A device of the character described, including in combination, a body portion and a handle, said body portion being composed of flexible netting of substantially rectangular shape, having its side and top edges bound with a soft, flexible material and having its lower corner portions folded along lines converging to a point and slightly overlapping, said handle member being in the form of a looped wire to provide the gripping portion and having its end portions free and positioned between the body portion and the folded corner portions, the end portions of the handle extending along lines on which the lower corner portions are folded and then bent and extended to substantially the intermediate part of the body portion, and securing means for connecting the upper edges of the folded corner portions to the body portion so as to hold these edges against the body portion and to hold the free end portions of the handle member therein, said securing means passing through the binding and the body portion and a strip of flexible material positioned on the side of the body opposite the binding in which the ends of the securing means are clenched.

In witness whereof, I have hereunto affixed my hand this 27th day of November, 1917.

ARTHUR W. CASH.
